UNITED STATES PATENT OFFICE.

GEORGE W. WILSON, OF LOS ANGELES, CALIFORNIA, ASSIGNOR OF ONE-HALF TO JAMES R. TOWNSEND, OF LOS ANGELES, CALIFORNIA.

RAILWAY CROSSING.

Application filed April 25, 1927. Serial No. 186,317.

The conventional and standard railway crossing comprises rail sections located and immovably secured at intersections of trackways for alinement with and to form continuations of the running rails of the trackways.

To provide for the free passage of the flanges of the wheels of rolling stock moving along one trackway across or relative to the rails of an intersecting trackway, clearances, or breaks, are formed in the surfaces of the heads of the several rail sections of the crossing, which clearances, or breaks, as interruptions of the tread surfaces of the rails, present dwells, or recesses, into which the wheels of rolling stock sink, or "drop," and are productive of the socalled "hammering," the cause of injury, damage, wear and destruction of equipment including both the trackway and rolling stock and which also is objectionable from the standpoint of noise.

Many expedients have been resorted to and many contrivances planned, and invented, toward the end of producing a rail crossing providing both the required clearance for the flanges of wheels and the uninterrupted carriage of the wheel treads over and across the flange clearance devices, all of which may be classified under two general heads, namely, those having rail surfaces engageable by the wheel flanges whereby the wheel flanges provide wheel support at the moment of the passage of the wheel treads across the flange clearance of an intersecting rail, and those in which the rails of the crossing are movable for selective alinement with the running rails of intersecting trackways.

The contrivances of the first mentioned class are not satisfactory because the sharp flanges of the wheels rapidly wear the rail surfaces provided for them to levels no longer useful in carrying the wheel treads over the flange clearances of intersecting rails, which made for the requirement of too frequent replacement with attendant expense.

The contrivances of the second mentioned class in which rails of the crossing provide wheel carrying conditions identical with the running rails of the trackways, require mountings, for the rails of the crossing, constructed as "turntables," involve vertical

axes; are expensive initially, cumbersome, difficult to operate and subject to displacement by end thrusts imparted by the passage of rolling stock thereover.

An object of my invention is to provide a railway crossing of simple, durable and inexpensive construction, which possesses the solidity and wearing qualities of the standard crossing without its objectionable hammering and noise and possesses the continuous wheel bearing surface and wheel flange clearance of the "turntable" type without its initial great expense, its bulky cumbersome construction, its difficulty of operation and its likelihood to displacement by rolling stock.

A further object is to provide a rail crossing having elements bearing fixed alined relation with the rails of trackways and which are bodily rotated to present wheel bearing surfaces of different characters whereby a minimum of moving parts serve to provide both continuous uninterrupted wheel supporting surfaces and wheel flange clearance for rolling stock passing in any direction thereover.

This invention provides a single crossing element with wheel bearing surfaces of different characteristics to be selectively positioned and to furnish continuous and uninterrupted wheel supporting surfaces and flange clearance for the wheels of rolling stock moving in any direction thereover.

Other objects, advantages and features of invention may appear from the accompanying drawings, the subjoined detailed description and the appended claims.

The accompanying drawings illustrate the invention.

Figure 1 is a plan view of a railway crossing constructed in accordance with my invention.

Fig. 2 is a perspective view of a fragment of the crossing showing the movable crossing element as set to provide continuous wheel flange clearance and continuous wheel tread supporting surfaces longitudinally of the element.

Fig. 3 is an enlarged transverse sectional elevation taken on line x^3 , Fig. 2.

Fig. 4 is a view similar to Fig. 2 showing the movable crossing element as set to pro-

vide continuous wheel flange clearance and continuous wheel tread supporting surface transversely of the element.

Fig. 5 is an enlarged transverse sectional elevation taken on line α^5 , Fig. 4.

Fig. 6 is a diagrammatical plan view, partly in section, showing means for operating the crossing elements.

1, 2, 3 and 4 designate the running rails of one trackway and 5, 6, 7 and 8 designate the running rails of a second trackway, crossing or intersecting, the rails 1, 2, 3 and 4, all of which are shown as of standard, or conventional, construction of T type; of themselves such rails form no part of my invention, except as combined with the crossing of my invention and may be of other types such as standard "groove" rails.

As shown a crossing element 9 is fixed to 20 aline with the rails 1 and 3 and extend across the rails 5 and 6, and similarly a crossing element 10 is fixed to aline with the rails 2 and 4 and extend across the rails 7 and 8.

The elements 9 and 10 are bodily rotatable 25 on horizontal axes and are provided with wheel tread supporting surfaces 11 and 12 for correspondence with the balls of the rails 1 and 3 and 2 and 4, respectively, as shown in Figs. 1, 2 and 3 and with wheel tread supporting surfaces 13 for correspondence with the balls of the rails 5, 7 and 6, 8, respectively.

In my preferred construction, and as shown, the elements 9 and 10 are of substantially cylinder form and are mounted for rotation in continuous bearings 14, of segmental trough-shape having base flanges 15 whereby they may be secured to supports, such as the sleepers, or ties 16, as by spikes 40 17, after the ordinary manner of securing running rails.

Crossing elements 18 and 19 are fixed to aline respectively with the rails 5, 7 and 6, 8, which by preference comprise bases 20, having flanges 21 for securement to the sleepers, and by further preference formed integral with the bearings 14, whereby the crossing as a whole may be handled and installed as "one piece."

Supported by the bases 20 of the elements 18 and 19 are caps 22 on the base of the crossing element 18, and 23 on the base of the element 19, which extended between the crossing elements 9 and 10; which caps are 55 removably and replaceably secured as by bolts 24 and bear wheel bearing surfaces 25 which sectionally correspond with the balls of the running rails and which have their terminals shaped to conform with the peripheries of the sectionally circular crossing elements 9 and 10 as best shown in Figs. 2 and 3.

Outside of the crossing elements 9 and 10 the bases 18 and 19 support caps 26, similar 60 to the caps 22 and 23, the inner terminals of

which are conformed with the crossing elements 9 and 10 and the outer terminals of which conform with and abut the running rails 5, 6, 7 and 8.

In Figs. 1, 2 and 3 the crossing elements 9 and 10 are shown as set for the passage of rolling stock, in either direction along the trackway of rails 1, 2, 3 and 4 and wherein the surfaces 11, 12 of the elements 9 and 10 are shown to register with the rails 1, 2, 3 and 4.

It is here pointed out that the widths of the surfaces 11 and 12 are substantially the same as the widths of the balls of the running rails and that the shaped terminals of the several caps 22, 23 and 26 are spaced distances greater than the widths of the surfaces 11 and 12.

This expedient provides for clearance of 85 the flanges of the wheels in moving across the wheel supporting surfaces of the caps.

In Figs. 4 and 5 the crossing elements 9 and 10 are shown as set for the passage of rolling stock over the rails 5, 6, 7 and 8, and with their surfaces 13 brought to register 90 with the rails 5, 6, 7 and 8. It is here pointed out that the surfaces 13, have greater widths than the described surfaces 11 and 12, and form flush continuations of the wheel bearing surfaces of the several caps.

When the elements 9 and 10 are in the position just recited, wheel flange clearance is provided by grooves or channels 27, formed transversely of the elements 9 and 10, and to lie immediately adjacent the wheel bearing surfaces of the caps.

When the elements 9 and 10 are set for 100 wheel travel over the rails 1, 2, 3 and 4, wheel flange clearance is provided by grooves or channels 28 extending lengthwise 105 throughout the elements 9 and 10 and lying next the wheel supporting surfaces 11 and 12 thereof.

To provide against endwise tipping of the elements 9 and 10, I form journals 29 at each 110 of their ends, which occupy bearings 30 formed in the base and over which I place caps 31, which are removably and replaceably secured as by screws 32, and which have formed thereon wheel bearing surfaces 33 for extension between the running rails 1 and 3 and the surface 11 of the element 9 and between the running rails 2 and 4, and the surface 12 of the element 10.

In Fig. 6, means are shown for turning the 120 elements 9 and 10 which consist of a solenoid 34 having opposed windings 35 and 36, a single core 37 and oppositely extended core stems 38 and 39. The stem 39 is directly connected to the element 10 and the stem 38 125 is connected to the element 9 through a motion reversing means 40.

Conductors 41 connected with the windings 35 and 36 may be extended to any suitable mechanism for control by rolling stock 130

as for example any approved, selective, switch throwing means.

I claim:—

1. A railway crossing comprising a substantially cylindrical element having a wheel bearing surface to form an uninterrupted continuation of aligned running rails, a second wheel bearing surface, circumferentially spaced from the first mentioned wheel bearing surface to form an uninterrupted continuation of relatively aligned running rails angularly disposed with relation to the first mentioned rails; and means for bodily rotating the element for selectively positioning the wheel bearing surfaces relative to the angularly disposed running rails.

2. A railway crossing comprising an element, bodily rotatable on a horizontal axis, having a longitudinally extending wheel bearing surface, a transversely extending wheel bearing surface having greater width than the longitudinal wheel bearing surface, running rails abutting the ends of the element, fixed crossing elements having wheel bearing surfaces conforming with the transversely extending wheel bearing surface of the rotatable element; and means for rotating the rotatable element for selectively positioning its wheel bearing surfaces relative to said running rails and the wheel bearing surfaces of the fixed crossing elements.

3. A railway crossing comprising relative-

ly angularly disposed base elements for alignment with the running rails of intersecting trackways, bodily rotatable elements removably and replaceably secured to a pair of said base elements, and caps having wheel bearing surfaces removably and replaceably secured to a second pair of said base elements.

4. A railway crossing comprising a pair of elements in fixed alignment with the running rails of a trackway, and extending between and beyond both running rails of an intersecting trackway, said elements provided respectively with distinct wheel tread supporting surfaces and means for bodily moving the elements to selectively bring their wheel tread supporting surfaces to align with the rails of either trackway.

5. In a railway crossing of the class described, a crossing element of substantially cylindrical form; a bearing providing rotatable support throughout the length of the element; means in the peripheral face of the element forming a wheel tread supporting surface extending the length of the element, and distinct means in the peripheral face of the element forming a wheel tread supporting surface extending transversely of the element.

In testimony whereof, I have hereunto set my hand at Los Angeles, California, this 14th day of April, 1927.

GEORGE W. WILSON.
